UNITED STATES PATENT OFFICE.

ALBERT C. BASSE, OF SAN ANTONIO, TEXAS.

BACON SLICER.

Application filed May 18, 1925. Serial No. 31,040.

To all whom it may concern:

Be it known that I, ALBERT C. BASSE, a citizen of the United States, residing at San Antonio, in the county of Bexar and State 5 of Texas, have invented a new and useful Bacon Slicer, of which the following is a specification.

This invention relates to a slicing machine especially designed for use in slicing bacon 10 or the like, the primary object of the invention being to provide a machine of this character to facilitate the slicing of bacon in a manner to insure slices of predetermined thicknesses.

15 An important object of the invention is to provide a machine of this character which may be manually operated, and one wherein the supporting member will be moved towards the rotary knife forming a 20 part of the invention, by a slight pressure exerted thereon, by the operator.

A still further object of the invention is the provision of means to move the slice which has been cut, from the machine, 25 thereby insuring against the slice becoming damaged by the support carrying the slice rearwardly through the machine, on the reverse movement of the support.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, may be made within the scope of what is claimed without departing from the spirit of the invention.

Referring to the drawings:

40 Figure 1 is a side elevational view of a slicing machine constructed in accordance with the invention.

Figure 2 is a section 2—2 of Figure 4.

45 Figure 3 is an elevational view illustrating the opposite side of the machine.

Figure 4 is a plan view of the machine, a strip of bacon being positioned on the support ready for passing through the machine.

50 Referring to the drawings in detail, the base of the machine is indicated generally by the reference character 5 and embodies an upper plate 6 and a lower plate 7, which plates are held in spaced relation with each other by means of the metallic strips 8 and

9 which are riveted thereto, by means of the rivets 10.

The rivets 10 also afford means for securing the bars 11 to the base, which bars are cut away to provide lateral extensions 12 60 that cooperate with the lateral extensions 13 of the bars 14 that are secured to the support or carriage, to be hereinafter more fully described.

The carriage embodies a plate 15 to which the bars 14 are secured so that the carriage may move longitudinally of the base to feed the meat supported thereon to the rotary knife. Extending upwardly from opposite sides of the carriage are arms 16 that are 65 provided with openings adjacent to the upper ends to accommodate the ends of the rod 17 that acts as a support for the meat engaging block 18, there being provided a metallic end member 19, which is bent to 70 provide a bearing for the block, positioned around the rod so that the meat engaging block will be permitted to swing vertically on the rod 17.

Carried by the meat engaging block are 80 prongs 20 that are adapted to embed themselves in the meat or article being sliced by the machine, so that movement of the block will be transmitted to the meat, to feed it laterally, after a slice has been made, so 85 that the meat will move to a position to be again sliced.

The reference character 21 indicates a handle carried by the meat engaging block 18 which may be grasped by the hand of the 90 operator to exert a pressure on the meat engaging block to embed the prongs in the meat so that the meat will be held against movement while the knife is operating to cut a slice.

95 Forming a part of the block is a plate 22 that extends upwardly therefrom, and provides a guard to prevent the operator's hand engaging the handle 21 from being cut by the knife.

100 In order that the slice cut from the piece of meat mounted on the carriage, will be moved from the machine, a laterally extended finger 23 is provided on the carriage to move therewith, which finger includes an upwardly extended flange 23' formed with teeth along the upper edge thereof. These teeth are arranged in such a way that they will bite into the slice of bacon which has 105 been cut by the machine and thrown into 110

the trough 24 mounted adjacent to the inner side edge of the base. It is to be understood that when a slice of bacon or meat has been cut by the machine, the slice falls into the trough 24 with one end of the slice extended beyond the forward end of the trough or in the path of forward travel of finger 23, which as before stated removes the slice from the machine.

10 Arranged adjacent to the knife, which is indicated at 25 is a guard plate 26 that guards against the slices cut from the meat moving laterally into the gearing, employed for operating the knife.

15 The operating mechanism is supported in the frame indicated generally by the reference character 27 on which frame are mounted the shafts 28 and 29, the shaft 28 being operated by means of the crank handle 30, 20 which is operated by the person using the machine.

25 Mounted on the shaft 28 is a gear 31 that meshes with the gear wheel 32 mounted on the shaft 29, which shaft also supports the knife 25, which is of the rotary type, as clearly illustrated by the drawings.

Clamps indicated at 33 are secured to the base, and provide means whereby the device may be secured to a suitable support such 30 as a table or the like.

The operation of the device is as follows: The device is clamped to a suitable support or table, and the bacon to be sliced is positioned on the carriage. The meat en-

gaging block is now moved into engagement 35 with the meat and the prongs embedded therein.

As the crank handle 30 is rotated, to rotate the blade 25, the carriage is moved along the base, with the result that the 40 meat is fed to the rotary knife which removes a slice therefrom, the finger 23 contacting with the slice to feed the slice through the trough 24.

I claim:-

1. A slicing machine including a base, a carriage mounted for sliding movement on the base, a rotary knife operating adjacent to one edge of the carriage, a trough disposed adjacent to the knife and adapted to 50 receive material cut by the knife, and a laterally extended finger operating adjacent to the trough for moving material through the trough.

2. A slicing machine including a base, a 55 rotary knife supported by the base, a carriage moving transversely of the base and adapted to support material under operation, a trough disposed adjacent to the knife and adapted to receive material cut 60 by the knife, and a finger carried by the carriage and adapted to engage material in the trough to move the material from the trough.

In testimony that I claim the foregoing 65 as my own, I have hereto affixed my signature.

ALBERT C. BASSE.
